UNITED STATES PATENT OFFICE.

FELIX GREMMELS, OF MANNHEIM, GERMANY, ASSIGNOR TO TECHNO-SERVICE CORPORATION, OF NEW YORK, N. Y., A CORPORATION OF NEW YORK.

BALANCED CLOSING DEVICE FOR WATER-CONDUITS.

1,392,637.

Specification of Letters Patent.

Patented Oct. 4, 1921.

Application filed May 28, 1920. Serial No. 385,081.

To all whom it may concern:

Be it known that I, FELIX GREMMELS, a citizen of the German Republic, and resident of Mannheim, in the German Republic, have 5 invented a certain new and useful Balanced Closing Device for Water-Conduits, of which the following is a specification.

This invention relates in general to a balanced closing device which is intended for 10 use in all such cases where a water-column exerts a high pressure upon the surfaces of the valve-disks and renders thus opening and closing the valves difficult. In particular my improved balanced closing device is intended for use in connection with water-conduits, such as by-pass conduits of chamber-sluices, bottom outlets of barrages, and the like, and it consists of disk-valves which are 15 arranged co-axially, or opposite to one another respectively, and the disks of which are connected with each other by stays, *i. e.* by a plurality of such ones, at least three whereby the effect of the water-pressure, *i. e.* of the cause of the resistance to motion, is done 20 away with. Means are provided for axially moving the disks of the valves, *viz.* in the direction of the stays, said means being located in the port between said disks, as is all 25 more fully described hereinafter.

30 In order to make my invention more clear, I refer to the accompanying drawings, in which similar letters denote similar parts throughout the several views, and in which:

Figure 1 shows by way of example a vertical section through one form of execution 35 of a balanced closing device constructed according to my invention; and

Fig. 2 is a horizontal section through the same.

40 The valves consist of disks c' and c'' and of seats d' and d'' which latter may be fastened to the masonry by concrete or the like. In the example shown it is assumed that a is the inlet port to the water-conduit 45 and b are outlet ports from the same, the port a being supposed to be vertical and the ports b being supposed to be horizontal and united with each other in a short distance from the closing device as may be imagined from the lower part of Fig. 2. Both 50 disks c' c'' are represented in full lines in that position in which they separate the port a from the ports b , or reversely. They are

connected with each other by a plurality of stays e (at least three, but preferably more, 55 for instance four, as in the example shown) supported and guided by standards f affixed to the bottom of the port a . Thus, also the disks c' c'' are axially guided by said standards with respect to the seats d' d'' . 60

A rack g extending parallel to the stays e is supported at both ends in the disks c' c'' ; and a cog-wheel h keyed to a vertical shaft i supported by a foot bearing k meshes with 65 said rack. By rotating the shaft i in the direction of the arrow (Fig. 1), the disks c' c'' are moved from the position shown in full lines to the position shown in dotted lines in which then the port a will be connected with the ports b b . 70

The disks c' c'' are of equal area, and the pressure of the water column in the port a upon the disk c' is equal to that upon the disk c'' , and reversely. Thus, the pressure exerted upon the disk c' is balanced by that 75 exerted upon the disk c'' , and reversely. In other words: the stays e are subjected to tensile strain by the pressing power acting upon the disks c' c'' from the port a . If, however, the direction of the water is reverse to that 80 indicated by the arrow in both figures, that is to say, if the water passes from the ports b b to and into the port a , then the stays e are subjected to compressive strain, as is clear 85 without a detailed explanation.

Having now described my invention, what I desire to secure by a patent of the United States is:

1. In a balanced closing device for water-conduits, in combination: two co-axially arranged disk-valves; stays connecting the disks of them with each other; guides for 90 said stays; and means for actuating said disks; said actuating means being arranged between said valves. 95

2. In a balanced closing device for water-conduits, in combination: two co-axially arranged valve-disks, means rigidly connecting the disks of same; a rack connected with 100 said disks; a cog-wheel meshing with said rack; and a shaft to which said cog-wheel is affixed; and means for turning said shaft.

3. In a balanced closing-device for water-conduits, in combination: two co-axially arranged disk-valves; a port between them; 105 two other ports at the other sides of said

valves; stays rigidly connecting the disks of said valves with each other; guides for said stays; a rack connected with the said disks; a cog-wheel meshing with said rack; and a shaft to which said cog-wheel is affixed; said shaft extending through said first-mentioned port.

In testimony whereof I affix my signature in presence of two witnesses.

FELIX GREMMELS.
